UNITED STATES PATENT OFFICE

2,071,911

AUXILIARY CIRCUIT

Hugh E. Young, Chicago, Ill.

Application March 24, 1934, Serial No. 717,280

3 Claims. (Cl. 171—97)

The present invention relates to illuminated safety signs and the like. A suitable example is a boulevard stop sign. The effectiveness of such a safety sign depends upon maintaining the 5 illumination. If an electric light be employed for such illumination, the burning out of the light kills the value of the sign. My invention aims to provide a simple means for bringing into action automatically and without any moving 10 parts a secondary lamp in case the primary lamp burns out.

The prime requisite in such a sign is reliability, i. e., continuity of performance. The ability to preserve the spare lamp without deterioration 15 while making it instantly and unfailingly available upon burning out of the primary lamp is an important aspect of my invention.

One feature of this invention is that failure of the primary lamp immediately causes illumination of an auxiliary lamp; another feature of this invention is that it employs no mechanical relays or moving parts of any kind; still another feature of this invention is that the auxiliary lamp has substantially no current flow there- 20 through while the primary lamp is functioning; still other features and advantages of this invention will appear from the following specification and drawing, in which—

The single figure is a diagrammatic view, illustrating the relation of the primary and auxiliary lamps.

In some particular fields of illumination, as for example through-street stop signs or theatre exit lights, it is desirable to have a second or 35 auxiliary lamp which will automatically function upon the failure of the primary lamp to illuminate the sign, yet draw no current while said primary lamp is functioning properly. This has been achieved by the use of relays of various forms, but much trouble has been experienced 40 due to corrosion and sticking of the contact points, and to other mechanical defects in the relays. This invention overcomes these previous defects by providing an electrical circuit 45 which is in perfect balance while the primary lamp functions properly, but when unbalanced by failure of the primary lamp causes the illumination of the sign by an auxiliary lamp.

In the embodiment of this invention illustrated 50 in the drawing, a primary lamp 10 is balanced by a variable resistance 11, which variable resistance is adjusted to match the impedance of the filament of the primary lamp. In series with the primary lamp and connected thereto 55 by a lead 14 is a fixed resistance 12, while the

variable resistance 11 has in series with it a second fixed resistance 13 connected thereto by a lead 15. These two series branches are connected in parallel to a source of electrical energy by the leads 16 and 17. An auxiliary lamp 18 5 is placed across the two branches by connecting it to the leads 14 and 15.

In the particular embodiment of this invention designed to be used in illuminating a through street stop sign, and to be operable from the 10 common commercial source of current at about 110 volts, the resistances 12 and 13 are of 1,000 ohms each; the filament resistance of the primary lamp 10 is of about the same value; the variable resistance 11 has a range permitting it 15 to be matched to the filament impedance of the primary lamp; and the auxiliary lamp 18 has a relatively low filament resistance, in the neighborhood of 50 ohms.

So long as the lamp 10 is not burned out, it 20 will continue to illuminate the sign by current flow from the wire 17 through the lamp 10, wire 14, resistance 12 and wire 16. Current will also flow through the resistances 11 and 13 in series, these resistances being bridged across the supply circuit 16 and 17. The lamp 18 is connected at equi-potential points, that is, at the midpoint between resistance 12 and lamp 10 25 at one end, and between resistance 13 and resistance 11 at the other end, whereby the lamp 18 normally has no current or substantially no current flow through it, and it will remain 30 indefinitely available for service.

In the event that the lamp 10 burns out, the 35 circuit becomes unbalanced and current will flow through the resistance 11, lamp 18 and resistance 12 in one branch, and through the resistance 13 alone in another branch to the return conductor 16. It will be observed that no movable parts, switching contacts or the like are required, and 40 that this circuit will bring the lamp 18 into play with the utmost reliability when the lamp 10 burns out. The operation of the device is entirely independent of voltage and over voltage 45 is not able to damage the lamp 18, since both terminals of the lamp are at the same potential so long as the lamp 10 is unimpaired.

The bridge circuit utilized in this invention does 50 not necessarily consist of resistance alone, but may have all or some of its legs composed of inductance or capacitance, or any combination of resistance, inductance and capacitance resulting in balanced impedances with the particular form of current being used.

What I regard as new, and desire to secure by Letters Patent, is:

- 5 1. A stop sign lighting circuit of the character described, including: two parallel branches, the first of which consists of a primary lamp and an impedance, said lamp being adapted to supply the desired illumination for the stop sign, and the second branch of which consists of a second impedance and a third impedance; and an auxiliary lamp in a circuit from the connection between the primary lamp and impedance in the first branch to the connection between the second and third impedances in the second branch, said auxiliary lamp having a much lower filament 10 impedance than said primary lamp and being adapted to illuminate said stop sign upon failure of said primary lamp.
- 15 2. A stop sign lighting circuit of the character described, including: a primary lamp and fixed impedance connected in series, said lamp having a filament impedance of substantially one thousand ohms and being adapted to supply the desired illumination for the stop sign with which the circuit is used; a variable impedance and a second fixed impedance connected in a second series, said second series being connected in parallel with said first series; a source of commercial A. C. power whereby said two parallel series are ener- 20 25

gized; and an auxiliary lamp connected from the juncture of said primary lamp and said fixed impedance to the juncture of said variable impedance and said second fixed impedance, said auxiliary lamp having a filament impedance substantially lower than that of said primary lamp and being adapted to furnish illumination for said stop sign upon the failure of said primary lamp. 5

3. The combination for illuminating a safety sign, comprising a current supply circuit, a primary lamp normally adapted to illuminate the sign by current flow therethrough, an impedance in series therewith, said lamp and impedance being connected in series and bridged across the supply circuit, a shunt circuit comprising two impedances connected in series and being bridged across the supply circuit, a stand-by lamp also adapted when energized to illuminate said sign, said stand-by lamp being connected to the two bridge circuits at equi-potential points whereby 10 the stand-by lamp is substantially free of current flow so long as the primary lamp is intact, said stand-by lamp being supplied with current flow by shift of potential of the points to which the spare lamp is connected by interruption of the 15 circuit through the primary lamp. 20 25
